Des. 240,868

Patented Aug. 3, 1976

240,868

COMBINED COMB AND HAIR SPRAY CANNISTER

Allan E. Legere, Swampscott, Mass., assignor to Cesari and McKenna, Boston, Mass.

Filed Oct. 17, 1973, Ser. No. 407,295

Term of patent 14 years

Int. Cl. D28—03

U.S. Cl. D86—10 A

Fig. 1.

Fig. 2.

FIG. 1 is a perspective view of a combined comb and hair spray cannister showing my new design; and

FIG. 2 is a perspective view in the opposite direction.

I claim:

The ornamental design for a combined comb and hair spray cannister, substantially as shown and described.
